GARMENT HANGER

Harold E. Kuss, Lock Haven, Pa.

Application May 12, 1943, Serial No. 486,677

5 Claims. (Cl. 223—89)

This invention relates to hangers for coats and other garments, particularly such garments as have sufficient value to justify a somewhat higher degree of care than is afforded by the ordinary coat hanger. The objects of the present invention are to provide correct support for the shoulders of coats and suits so that they will not lose their shape; to adjust the same for various types and sizes, and to provide a hook which can either be used in the normal way or swiveled on its vertical axis or tipped or swung on a transverse axis, to permit the body of the hanger to remain in the usual position even when it is hung against a wall over intervening other garments. This is facilitated by a special hook tip to accommodate particular conditions. Further objects are to provide quick acting supplemental trouser or skirt bars capable of exerting a uniform clamping pressure, and to also provide automatic hooks by which the hanger can be clamped to a clothes line and prevented from sliding along a cord or pulley line when the garment is hung out to sun or dry. This keeps the garments definitely separated instead of crowding together as with ordinary hangers. Additional objects incidental thereto will become apparent as the description proceeds. In general the objects are to improve the utility and convenience of garment hangers.

In the drawing forming part of this specification,

Fig. 1 is a general perspective view from the front and slightly from above so as to show the tilting hook base inserted in the neck portion, together with the other features.

Fig. 2 is a cross-sectional view at right angles to Fig. 1, taken thru the neck portion to show the tilting and swivelling hook base construction.

Fig. 3 is a front elevation of the line lock mechanism in the unlocked position.

Fig. 4 is a side elevation of the line lock mechanism shown in the unlocked position in solid lines and in the locking position in dotted lines.

Fig. 5 is a detail cross-section on the line 5—5 of Fig. 1 showing a dove-tail feather key guide for the movable shoulder portions.

Similar reference numerals refer to similar parts thruout the various views.

Referring now to Fig. 1, the hanger consists of a main frame 1 formed and moulded to fit the neck and shoulder portions of the usual garment and provided with movable shoulder tips 2 mounted on dove-tailed keys or guides 3, as shown in cross-section in Fig. 5. These shoulder tips 2 are conformed to a normal shoulder shape and can

be adjusted to different breadths of shoulders by means of the turnbuckle 4 operating the rods 5 and 5¹ which are provided with screw threads 6 and 6¹ having opposite pitch. These rods 5—5¹ extend loosely thru the frame 1 and are secured to the shoulder tips 2 so that they cannot turn but are moved in and out by means of the turnbuckle 4 operating on the threaded portions of the rods. One good hanger can thus fit coats of various sizes.

In the moulded neck portion of the hanger there is inserted an arcuate base 8 for the hook 9 as shown in Fig. 1 and Fig. 2. This hook base 8 is pivoted on a transverse pivot pin 10 so that the base 8 may tilt in a plane at right angles to the plane of the garment. This permits the garment to hang normally even when the hook portion of the hanger is tipped back over other hangers on the same wall hook. Sometimes several hangers are hung on the same hook on a wall, and the tilting hook in the present device not only permit its own garment to hang better but also avoids pinching the garments on other hangers.

The hook 9 is mounted on a swivel 12 on the base 8 so that it may turn freely in any direction. This swivel 12 has a collar 13 bearing against the thrust plate 14 which may be made of a metal strap 15 extending around and secured to the base 8 and over the collar 13 so as to take the load.

The hook 9 extends up and over in the usual curve to hang on rods and also carries at its tip a metal ring or loop 16 pivoted to swing freely on the end of the hook. This tip 16 is useful for attaching to wall hooks, particularly when several hangers are crowded on the same wall hook. With ordinary hangers there is a tendency for the outer one to fall off and also to crush the necks of the garments on the underlying hangers.

In the present device, with the combination of the tiltable hook base and the swinging tip these difficulties are to a considerable degree overcome.

On the neck or shaft of the hook 9 there is constructed an automatic line lock mechanism 20 as shown in Fig. 1 and Fig. 2 but more in detail in Fig. 3 and Fig. 4. The purpose of this mechanism is to grip or lock the hanger to the clothes line on which the garment is hung so that it will not slide along and crowd other garments; and also so that it can be used on pulley lines such as are common in cities. Referring now particularly to Fig. 3 and Fig. 4, the shaft of the hook 9 is provided with a sliding sleeve 21 to which is securely affixed a hook 22 and a cross-bar 23. These elements 22 and 23 move with the sleeve 21. A

short distance above the sleeve 21 are a pair of movable fingers 24 mounted on a cross-pivot pin 25. These fingers 24 rest over the cross-bar 23, and if the sleeve 21 is slid upward the cross-bar 23 raises the fingers 24 to a horizontal position as shown in Fig. 4 by broken lines.

The operation is as follows: If the hook 22 is placed over a clothes line 30 (see Fig. 4) and the hanger released, the weight of the garment or hanger pulls the hook 9 down thru the sleeve 21, and the relative motion of the sleeve 21 is upward on the neck of the hook 9. This swings the fingers 24 to the horizontal position shown in broken lines in Fig. 4 and securely clamps the clothes line 30 between the hook 22 and the fingers 24. This holds the hanger and garment in its place on the line so that it can be safely used on a movable pulley line or a sagging line.

The hanger is also provided with an improved trouser or skirt clamp consisting of clamping rods 35 which can be pinched together by sliding down the pinch link 36. These rods 35 do not extend straight across as in the ordinary hanger but are curved slightly toward each other, that is convexed together. This configuration greatly enhances the clamping effect of the pinch links 36. Ordinary rods when pinched together at the ends tend to compress the clothes unevenly and bulge in the center where the pressure or leverage is less. By this improvement a substantially uniform pressure can be exerted all the way across the garment clamped, even with a relatively light wire structure.

It will be seen that a hanger constructed as above described affords a degree of protection and care to garments of value not found with simple hangers of the ordinary type. While I have in the foregoing described a certain specific form of hanger by way of example, it will be understood that it is merely for purposes of illustration to make clear the principles of the invention, which is not limited to the particular form shown, but is susceptible to various modifications and adaptations in different applications as will be apparent to those skilled in the art, without departing from the scope of the invention as stated in the following claims.

I claim:

1. In a hanger for garments, the combination of shoulder portions, a moulded neck portion, a transverse pivot in said neck portion, said pivot lying in the main plane of the hanger, a tiltable

hook mounted on said pivot for tilting in a plane at right angles to the main plane of the hanger, a swinging tip loop on the end of said hook, whereby a garment on the shoulder and neck portions may remain vertical while the hook is tilted at various angles.

2. In a hanger for garments, the combination of movable shoulder portions, a turnbuckle connecting said portions for adjusting them, a moulded neck portion, a transverse pivot in said neck portion, the axis of said pivot being substantially parallel to the axis of the turnbuckle, a tiltable base mounted on said pivot, a thrust plate on said base, a swivelling hook having a collar engaging said thrust plate, so that the hook can turn in any direction, and a pivoted loop on the tip of said hook, whereby a garment on the shoulder and neck portions may remain vertical while the hook and tip loop are swung and turned in various directions.

3. In a hanger for garments, the combination of a neck portion, shoulder portions, a hook having a shank attached to said neck portion, a sliding sleeve on said shank, and a line clamping mechanism comprising a clamping hook and a pivoted locking member operated by said sleeve when a load is placed on the hook, whereby the hanger may be securely clamped to a line to prevent sliding thereon.

4. In a hanger for garments, the combination of a neck portion, shoulder portions, a hook having a shank attached to said neck portion, a sliding sleeve on said shank, a clamping hook, and a pair of pivoted fingers operated by said sleeve, whereby the hanger may be securely clamped to a line by said fingers pressing the line against said clamping hook.

5. In a hanger for garments, the combination of a moulded neck portion, a tilting and swivelling hook attached to said neck portion, a line clamp lock on said hook, a pivoted tip loop on the end of said hook, a pair of adjustable shoulder portions, a turnbuckle for adjusting said shoulder portions, a garment clamp beneath said hanger comprising flexible elements convex toward each other so as to be closer at the middle portions than at the ends, and clamps near the end portions of said flexible elements, whereby the curvature of the clamping elements offsets the yielding of the middle portions under pressure.

HAROLD E. KUSS.
